UNITED STATES PATENT OFFICE.

HARRY RANDOLPH VAN DEVENTER, OF SUMTER, SOUTH CAROLINA, ASSIGNOR TO
SPLITDORF ELECTRICAL COMPANY, OF NEWARK, NEW JERSEY, A CORPORATION
OF NEW JERSEY.

GENERATING AND LIGHTING DEVICE.

1,249,861.

Specification of Letters Patent. Patented Dec. 11, 1917.

Application filed September 6, 1916. Serial No. 118,699.

To all whom it may concern:

Be it known that I, HARRY RANDOLPH VAN DEVENTER, a citizen of the United States of America, residing at Sumter, in the county of Sumter and State of South Carolina, have invented certain new and useful Improvements in Generating and Lighting Devices, of which the following is a specification.

10 This invention relates to generating and lighting devices for use with bicycles, automobiles and other vehicles.

The objects of the invention are to provide a unitary structure comprising a dynamo and a lamp adapted to be mounted on a vehicle and driven by a moving part, such as a wheel, thereof; to provide a structure in which the lamp is carried by the moving part of the dynamo, and the latter is driven 20 by a moving part of a vehicle; and to provide a support for said structure including resilient means for holding the same in driving relation to the vehicle wheel or other moving part.

25 These and other objects of the invention are attained by the arrangement and combination of parts hereinafter more fully described and pointed out in the appended claims.

30 The invention is illustrated in the accompanying drawings, in which:—

Figure 1 is a sectional view illustrating the generating and lighting structure in relation to the coöperating parts of a bicycle, 35 and

Fig. 2 is a plan view of the magnet and armature structures.

In the arrangement shown in the drawings, the dynamo or generator comprises a plurality of permanent magnets 1, punched from sheet stock into the ring-shaped form shown in Fig. 2 and assembled into a group, as in Fig. 1, each magnet having poles N and S. Secured to the magnet group by 40 screws or the like 2, shown in Fig. 2, are non-magnetic end plates 3 and 4, these plates together with the magnet group forming an inclosing chamber or casing.

Within this chamber or casing, is located 50 an armature structure comprising an iron armature 5, carrying a generating or winding coil 6, and non-magnetic heads 7 and 8 secured to the armature by screws or the like 9, Fig. 2. Riveted or otherwise secured to

the heads 7 and 8 are shafts 10 and 11, which 55 pass through bearings in the end plates 3 and 4 respectively. The shaft 10 carries a drive wheel 10^a adapted to frictionally engage the tire 12 of the vehicle wheel, whereby the armature structure is rotated as the 60 wheel revolves. The shaft 11 is formed at its upper end to receive the lamp 14.

One end of the generating or winding coil 6 is connected directly to the terminal or connector 15 which is surrounded by the insulating sleeve 15^a carried by the shaft 11, and the base terminal 16 of the lamp 14 directly engages the upper end of this terminal 15.

Secured to or forming part of a support 70 17 which incloses the upper end of the shaft 11, and is secured to or forms part of the end plate 3, is a reflector 18 having an aperture 19 through which the lamp 14 projects, and this reflector carries at the front there- 75 of a lens 20.

The end plates 3 and 4 are provided with extensions 21 and 22 which are secured by bolts 23 to a barrel 24, the latter having an arm 25 formed at its rear end as part of the 80 usual form of clamp secured by the bolts 26 to the front bar or tube 27 of the bicycle frame. The barrel 24 is hollowed at its upper and lower ends and receives springs 28, which are connected to the barrel at their 85 inner ends and to the extensions 21 and 22 at their outer ends. The springs 28 are so arranged as to hold the drive wheel 10^a in driving contact with the tire 12.

It will be seen that the reflector 18, support 90 17, end plates 3 and 4 and magnet group 1 form a housing or casing within which the dynamo parts and lamp are entirely inclosed, the whole forming a unitary structure comprising generating, lighting 95 and reflecting elements, adapted to be supported on a vehicle and to be yieldingly held in driving engagement with a moving part of such vehicle. The construction is extremely compact, easily manufactured and 100 assembled, and there are no exposed electrical terminals and connections, which might be easily damaged or broken. By mounting the lamp on the moving part of the dynamo and in direct contact with the 105 terminal of the generating coil, sliding contacts or brushes, connecting wires and the like are entirely avoided. All of the parts

are completely inclosed and protected from dust and dirt, which is of particular advantage in the case of a lighting structure located in close proximity to the wheel of a vehicle.

It will be understood that the invention is not limited to the particular construction of parts shown, which may be widely varied within the scope of the appended claims.

10 1. I claim:—

1. A generator lamp comprising a casing, a reflector mounted on said casing, a dynamo having a rotatable part carrying a generating coil located in said casing and extending 15 at one end into said reflector, a driving wheel attached to the other end of the rotating part and adapted to engage a rotating part of the vehicle, said rotatable part of the dynamo being disposed in a plane at 20 right angles to the plane of the rotating part of the vehicle and a lamp disposed in said reflector and carried by said rotatable part and having connection with the generating coil.

25 2. A generator lamp comprising a dynamo having a rotatable part, a generating coil mounted on said rotatable part, a driving wheel connected to one end of said rotatable part, a lamp mounted on the other 30 end of said rotatable part to rotate therewith, and having connection with the generating coil, and a magnet disposed in a plane at right angles to the axis of rotation of said rotatable part.

35 3. A generator lamp comprising a dynamo having a rotatable part, a generating coil mounted on said rotatable part, a driving wheel connected to one end of said rotatable part, a lamp mounted on the other 40 end of said rotatable part to rotate therewith and having connection with the generating coil, and ring magnets surrounding said generating coil.

45 4. A generator lamp comprising a dynamo having a movable part mounted to rotate about a vertical axis, a generating coil carried by said movable part, sheet metal ring magnets located in a horizontal plane and surrounding said generating coil, a driving wheel connected at the lower end of said movable part and adapted to engage the rotating part of a moving vehicle, and a lamp mounted on the upper end of said 50 rotating part to rotate therewith, said lamp having connection with the generating coil.

55 5. A generator lamp comprising a dynamo having a movable part mounted to rotate about a vertical axis, a generating coil carried by said movable part, magnets located in a horizontal plane and surrounding said generating coil, a driving wheel connected at the lower end of said movable

part and adapted to engage the rotating part of a moving vehicle, and a lamp mounted on the upper end of said rotating part to rotate therewith, said lamp having connection with the generating coil, and a housing inclosing the dynamo and the lamp, said housing including a vertically disposed reflector for the lamp.

6. A generator lamp comprising a dynamo having horizontally disposed magnets, an armature mounted to rotate about a vertical axis within said magnets, said dynamo having end plates secured to the magnets 75 and projecting rearwardly therebeyond for forming an attaching means for securing the dynamo to a vehicle, a driving wheel secured to the lower end of the armature shaft and adapted to engage a rotating part 80 of the vehicle, a lamp fixed to the upper end of said armature shaft to rotate therewith and having connection with the generating coil of the armature, a support carried by the upper end plate, and a vertically 85 disposed reflector mounted on said support and having an opening in its lower side through which the armature shaft projects, whereby the lamp may be disposed vertically within the reflector.

90 7. A generator lamp comprising a dynamo having a rotary generating coil provided with a vertical shaft having a drive wheel on its lower end, a suitable casing for the generator, a vertically disposed reflector on top of the casing, the upper end of the rotary shaft extending up through the casing into the lower rear part of the reflector and provided with a lamp socket in its upper end, a conductor extending through 100 the shaft, connected at its lower end to the coil winding and extending at its upper end into the lamp socket, and a lamp mounted in said socket with its terminal engaging said upper end of the conductor.

105 8. A generator lamp comprising horizontal ring magnets, a vertical shaft having a generating coil within the magnets, an operating wheel on the lower end of the shaft, a lamp on the upper end of the shaft to turn therewith and connected to the said coil, top and bottom plates secured together and inclosing the magnets, said plates having rearward extensions, a supporting arm having an attaching device and provided with a vertically sleeved portion extending between said rearward extensions, a bolt extending through the sleeve and the said extensions, and a spring on the bolt within said sleeve and engaging the sleeve and said 110 extensions to hold the wheel against a rotary actuating means.

In testimony whereof I affix my signature.
HARRY RANDOLPH VAN DEVENTER.
